UNITED STATES PATENT OFFICE

BERTHA SAUNDERS, OF HOLLYWOOD, CALIFORNIA

HAIR WAVER

Application filed April 5, 1932. Serial No. 603,240.

The present invention has to do with hair wavers of the "permanent" wave type such as disclosed in my co-pending applications for patent, bearing Serial Numbers 541,354 and 569,651 and filed June 1, 1931 and October 19, 1931, respectively.

An object of this invention is to provide a hair waver of comparatively simple, compact and inexpensive form by means of which a flat, natural wave of lasting and uniform characteristics and of better appearance may be provided in a more efficacious manner than has heretofore been possible.

Another object of the invention is to provide a hair waver such as described, wherein the members or portions on which the hair to be treated is wound are of a new construction and arrangement calculated to facilitate not only an easy winding of the hair thereon but to effect a retention of the hair in such form as to insure the formation of a long lasting wave of natural appearance.

A further object of this invention is to provide a hair waver which will produce waves of such great extent and of such a nature that when the expected and usual loss of the curl or wave takes place, on washing the hair, there will remain a full flat wave of the desired natural appearance.

Still another object is to provide a hair waver such as described, wherein the members on which the hair to be waved is wound are of such shape and arrangement as to produce waves free from sharp angles or front or reverse sides, the waves formed thereby being of uniform characteristics and presenting the desired appearance regardless of the position in which the strands of hair lie or hang.

Yet another object is to provide a waver of the character described wherein the particular cylindrical wave forming members are comprised of complementary halves which are subject to ready separation after the hair is wound thereon, whereby to stretch and hold the hair under tension on the waver.

Another object is to provide a hair waver wherein parts thereof are subject to relative movement by manipulation of a novel means which is easily operable after the hair is

wound on the waver, whereby to place the hair under tension without causing any discomfort to the person whose hair is being waved, or distorting the hair from the desired formation on the waver, or causing the sharp angles or bends in the finished wave.

Another object is to provide a hair waver such as described where provision is made for forming an effective wave at the extreme end of the hair strand which is tied on the waver.

A further object of the invention is to provide a method for waving human hair in which a series of portions of a strand of hair are coiled and the individual coils subjected to a stretching action during heat treatment of the hair.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Fig. 1 is a plan view of the waver;

Fig. 2 is a longitudinal section on line 2-2 of Fig. 1;

Fig. 3 is a cross section on line 3-3 of Fig. 1;

Fig. 4 is a cross section on line 4-4 of Fig. 1;

Fig. 5 is a view in side elevation showing the parts in the hair stretching position;

Fig. 6 is a plan view showing the manner of applying the hair to the waver;

Fig. 7 is a diagram illustrating the mode of applying the hair.

In carrying out the embodiment of the invention shown in detail in the accompanying drawing, a body portion A comprised of flat bars 8 and 9 laid one upon the other, is employed to support sectional and expandible hair receiving posts 10 constituting wave forming members in such manner that the sections of the posts will be moved apart whereby to stretch the hair thereon, when a means 11 attached to and serving as a

handle for the body portion is manipulated to move one of said bars longitudinally relative to the other.

As here shown, the posts 10 are spaced apart 5 along the plate 8 and are composed of semi-cylindrical halves 12 and 13 of which the halves 12 are fixed to the bar 8 by pins 14 and the halves 13 are fixed to the bar by pins 15. The pins 15 extend through slots 16 in 10 the bar 8 whereby the bar 9 and halves 13 are subject to movement relative to the bar 8 and halves 12 thereon. It will now be seen that when the halves 12 and 13 are in substantial engagement with one another the 15 posts 10 are of cylindrical form providing for an easy winding of the hair thereon. However, upon moving the bar 9 the halves 12 and 13 will be spread apart whereby to stretch the hair wound on said posts. This places 20 the hair under tension and provides for the formation of a better and more lasting wave effect in the hair.

The means 11 for moving the bar 9 as aforesaid comprises an internally screw 25 threaded tubular member 17 which is rotatably fixed in a collar 18 in turn fixed on one end of the bar 8. On the corresponding end of bar 9 is a screw threaded extension 19 which is threadedly engaged in said tubular 30 member 17. On turning the tubular member 17 the bar 9 will be moved longitudinally of the bar 8 and, in the present arrangement, clockwise movement of said member 17 will slide bar 9 so as to move the halves 12 35 and 13 apart, whereas anti-clockwise movement will draw said halves together. The tubular member 17 is knurled as at 20 on its outer end to facilitate the manipulation thereof.

40 At the outer end of the bar 8 is a slotted extension 22 which facilitates tying the strand of hair to the waver. At the other end of this bar is a small cylindrical post 23 which provides for winding and securing the end 45 of the strand in such manner as to insure the desired wave formation at the extreme end of the strand.

The posts 10 are formed with concave 50 channels extending circumferentially thereof which serve to prevent the hair strands from sliding off the ends thereof and also facilitate positioning of the strands thereon, while the end post 23 is formed with a flange 25 at its outer end for a like purpose.

55 The leading end post 10 is formed with a lip 26 which protrudes from its outer end in the direction of the length of the bar 8, which lip serves to retain the initial convolution of the strand wound on this post 10 in place.

60 As a means for preventing hair from catching between the inner ends of the post sections 13 and the bar 8, the latter is formed with upstanding flanges 27 along its longitudinal edges.

65 Best results have been obtained by tying

the hair strand close to the head on the extension 22, and then winding the strand around the posts 10 and 23, as shown in Figs. 6 and 7, the hair then being tied to the post 23 in any suitable manner. In winding the hair 70 on the posts 10, it is preferably wound in reverse convolutions on adjacent posts 10, as depicted in Fig. 7. With the hair thus wound to make complete loops around each post, the member 17 is turned to expand the posts 10, as aforesaid, and thereby stretch the individual loops of the hair encircling each of 75 said posts. The hair is now held under tension and the usual permanent waving treatment and operations are now carried out, the stretching of the hair and the holding thereof under tension making for a quicker and more effective response of the hair to the treatment. This waving operation embodies 80 the usual steps of subjecting the stretched hair to a steaming action then releasing the hair and washing it to remove a portion of 85 the resultant curl.

The waver is equipped with any suitable 90 number of the stretching posts 10 as occasion may require, according to the length of hair 95 to be waved.

It will now be seen that the device hereof 95 will provide for the objects and advantages 100 of the invention in a particularly efficacious manner.

It is to be noted that the device is characterized by the embodiment of a pair of relatively slidable bars carrying two piece posts 105 protruding from one side thereof which posts constitute stretching forms of general cylindrical shape, whereby the hair on being wound around a post in a single convolution and being held at its ends may be placed under tension throughout the length of the convolution so that the formed curl will be free 110 of angles.

I claim:

1. In a hair waver, a pair of parallel bars one of which is movable longitudinally relative to the other, a row of spaced wave forming members arranged along the length of 115 said bars and protruding from one side thereof, each member comprising a pair of sections one of which sections is movable relative to the other and is fixed to the movable bar, and means for moving one of said bars longitudinally relative to the other bar.

2. In a hair waver, a body portion 120 comprised of a pair of elongated bars mounted one upon the other for longitudinal movement relative to each other, and one of which is provided with slots, a plurality of cylindrical wave forming members around which is wound the hair to be waved, each of said members comprising a section fixed on the slotted bar, and another section fixed to the other bar, fastenings for securing the second 125 named sections being extended through said 130

slots, and means for moving said bars longitudinally relative to each other.

3. In a hair waver, a body portion comprised of a pair of elongated bars laid one upon the other, a row of cylindrical wave forming members arranged to project from one of said bars and adapted to have the hair to be waved wound therearound, each of said members comprising a pair of sections one of which is movable towards and away from the other, means for fixing certain of said sections to one bar, one of said bars having slots therein, means slidable in said slots for fixing the other sections to the other bar, a tubular internally screw threaded member, means for rotatably fixing said tubular member to one end of one of said bars, and a screw threaded portion extended from an end of the other bar and having threaded engagement with said tubular member.
4. In a hair waver, a body portion, a plurality of spaced cylindrical wave forming members on said body portion, each member comprising two semi-cylindrical sections one of which is movable relative to the other, means for so moving said movable sections, and laterally extending flanges on the outer ends of said members and operatively to prevent the hair from slipping off said members.
5. In a hair waver, an elongated body portion, a plurality of spaced wave forming members on said body portion, each member comprising two sections arranged side by side in the direction of the length of said body portion one of which is movable relative to the other, means for so moving said movable sections, and upstanding flanges on the longitudinal edges of one of said bars projecting on opposite sides of said members.
6. In a hair waver, a pair of parallel slide

bars disposed face to face, means for effecting relative longitudinal movement of said bars, and a post protruding from one of said bars formed of separable semi-cylindrical sections one of which sections is carried on one of said bars and the other of which is carried on the other of said bars, said post being formed with a hair receiving circumferential channel.

7. In a hair waver, a pair of slide bars disposed face to face, means for effecting relative longitudinal movement of said bars, slots formed in one of said bars, upstanding side flanges on said slotted bar, a divided hair stretching post protruding from between said flanges one member of which is carried on said slotted bar and the other of which is carried on the other bar through said slots.

8. In a hair waver, an elongated bar, a series of semi-cylindrical projections carried by and affixed to said bar and protruding from one side thereof, a second elongated bar arranged on one side of said first named bar in slidable relation thereto, a series of semi-cylindrical projections carried by and affixed to said last named bar protruding parallel with said first named projections and coacting therewith to form a series of spaced substantially cylindrical wave forming members around which a strand of hair to be waved may be wound to completely encircle each of said members, means independent of said projections to which a strand of hair may be secured adjacent the ends of said bars, and means for shifting said bars longitudinally relative to each other to effect spacing of complementary pairs of the projections and to stretch the individual circlets of hair thereon.
